United States Patent Office

ISAAC A. HORN, OF CINCINNATI, OHIO.

Letters Patent No. 78,094, dated May 19, 1868.

IMPROVED PLATE FOR ARTIFICIAL TEETH.

The Schedule referred to in these Letters Patent and making part of the same.

TO ALL WHOM IT MAY CONCERN:

Be it known that I, ISAAC A. HORN, of Cincinnati, in the county of Hamilton, and in the State of Ohio, have invented certain new and useful Improvements in Plates for Artificial Teeth; and do hereby declare that the following is a full, clear, and exact description thereof, reference being made to the accompanying drawings, and to the letters of reference marked thereon.

In the annexed drawings, forming part of this specification, the plate of an upper set of teeth is represented. This plate, which is to be made of any material that may be used in artificial dentistry, is provided with suction or vacuum-chambers A A, constructed in the rim, so as to operate against both cheek and outer or buccal portion of the alveolus, by making grooves, furrows, or recesses, and communicating the same by a channel to the inner chamber, B, or inner edge of the plate. This, together with the sharp ridge C, on the outer rim of the plate, running from the anterior to the posterior of the same, inclining downward toward the cutting-edge of the teeth, for the purpose of preventing food, especially hard particles, from passing over the upper edge of the plate.

These suction or vacuum-chambers can be placed in the plate, as above described, or in what is called cheek-restorers, which are added to the plate in case of impaired sense of taste, nausea, coughing, sneezing, &c.

Having thus fully described my invention, what I claim as new, and desire to secure by Letters Patent, is—

The suction or vacuum-chambers, operating against the cheek and alveolus, and the sharp ridge on the outer rim of the plate, these to be made of any material used in dentistry, substantially as and for the purposes above set forth.

In testimony that I claim the foregoing, I have hereunto set my hand, this second day of April, 1868.

ISAAC A. HORN.
